(57) **CLAIM**

The ornamental design for a wheel or wheel cover, as shown and described.

DESCRIPTION

FIG. 1 is a front view of a first embodiment of a wheel or wheel cover according to my novel design; and

FIG. 2 is a perspective view thereof.

FIG. 3 is a front view of a second embodiment of the wheel or wheel cover according to my novel design; and,

FIG. 4 is a perspective view thereof.

The broken line showing of the rear of the rim and the bolt holes and center hole in the central hub area is included for the purpose of illustrating environment and forms no part of the claimed design.

1 Claim, 2 Drawing Sheets

FIG. 1

FIG. 2

FIG. 3

FIG. 4
